UNITED STATES PATENT OFFICE.

JOHN J. FITZGERALD, OF BROOKLYN, NEW YORK.

TABLE-COVER.

1,217,932.

Specification of Letters Patent.

Patented Mar. 6, 1917.

Application filed December 21, 1915. Serial No. 68,018.

To all whom it may concern:

Be it known that I, JOHN J. FITZGERALD, a citizen of the United States, and residing at Brooklyn, in the county of Kings and State of New York, have invented certain new and useful Improvements in Table-Covers, of which the following is a specification, such as will enable those skilled in the art to which it appertains to make and use the same.

This invention relates to covers for tables and particularly for dining room tables, and the object thereof is to provide an improved device of this class that may be applied to the table whenever desired, and detached therefrom when not desired and which will protect the surface of the table; a further object being to provide a device of the class specified which may be compactly folded up when not in use; and with these and other objects in view the invention consists in a device of the class specified, constructed as hereinafter described and claimed.

The invention is fully disclosed in the following specification, of which the accompanying drawing forms a part, in which the separate parts of my improvement are designated by suitable reference characters in each of the views, and in which:

Figure 1 is a plan view showing one form of my improved table cover with part broken away;

Fig. 2 a view similar to Fig. 1 but showing a modification;

Fig. 3 a side view of a table with the cover shown in Fig. 1 applied thereto and in section on the line 3—3 of said figure.

Fig. 4 a view similar to Fig. 3 but showing the cover indicated in Fig. 2, said cover being sectioned on the line 4—4 of said figure;

Fig. 5 a view showing the cover shown in Fig. 1 folded once; and,

Fig. 6 a view showing the framework of the cover shown in Fig. 2 folded twice.

In the accompanying drawing, I have shown at *a* a table which is circular in form and provided with a depending skirt portion *a*² of less dimensions than the table proper, and said table is provided with and supported by a standard *a*³ which is only partially shown.

In the practice of my invention, as shown in Figs. 1, 3 and 5, I provide a cover *b* comprising a frame or rim portion *b*², a top

fabric member *b*³ and an inner, bottom padding, or cushioning member *b*⁴.

The rim portion *b*² of the cover, in the construction shown, is composed of two separate parts hinged together at *b*⁵, and with this construction the complete cover shown in Fig. 1 may be folded together as shown in Fig. 5. The top fabric member *b*³ is folded around the rim portion *b*² as shown at *b*⁶ and may be secured thereto in any desired manner, and the padding or cushioning member *b*⁴ may be secured to the fabric member *b*³ and the rim portion *b*² in any desired manner.

From the extended or operative position of the table cover *b*, as shown in Figs. 1 and 3, said cover may be folded into the position shown in Fig. 5 on the hinges *b*⁵ in which operation the top or fabric faces of said cover are brought together.

In the construction shown in Figs. 2, 4 and 6, the padding or cushioning member *b*⁴ is omitted and the frame or rim portion *b*² is composed of four parts hinged together at *b*⁵ and *b*⁷, said hinges at *b*⁷ being clearly shown in section in Fig. 4, whereby the frame or rim portion may be folded, as shown in Fig. 6, thereby producing a more compact frame than that shown in Fig. 5, and it will be understood that the frame shown in Figs. 2, 4 and 6 is first folded on the hinges *b*⁵ into the position shown in Fig. 5, after which the two halves of the frame or rim portion are folded on the hinges *b*⁷ into the position shown in Fig. 6.

The frame or rim portion *b*² may be composed of metal, wood, or any other suitable material, and while I have shown and described the frame or rim portion composed of separate parts adapted to be folded together, it will be understood that said frame or rim portion may be made continuous or without folding means, and while I have shown said table cover adapted for use in connection with a round table, it will be understood that the shape or form of said cover may be varied and used in connection with tables of any desired form and construction.

Having fully described my invention, what I claim as new and desire to secure by Letters Patent, is:

1. A detachable table covering, comprising a fabric sheet in the edge portion of which is secured an annular frame or rim portion,

said frame or rim portion being composed of four similar parts hinged together, whereby said covering may be first folded centrally and transversely and the folded parts again folded in the plane of the frame or rim portion to form a compact package.

2. In a device of the class described, an annular frame divided up into four similar arc-shaped parts hinged together whereby said frame may be first folded into two parts and again folded at right angles to said first fold to bring the folded parts together, and

a fabric sheet, the edges of which are connected with the inner faces of said frame or the separate arc-shaped parts thereof.

15

In testimony that I claim the foregoing as my invention I have signed my name in presence of the subscribing witnesses this 18th day of December 1915.

JOHN J. FITZGERALD.

Witnesses:

C. MULREANY,
H. E. THOMPSON.
